UNITED STATES PATENT OFFICE.

FREEMAN S. HUNTER, OF BEDFORD, INDIANA, ASSIGNOR OF ONE-HALF TO OLIVER P. HUNTER, OF BEDFORD, INDIANA.

METALLIC RAILROAD CROSS-TIE.

1,094,719.

Specification of Letters Patent. Patented Apr. 28, 1914.

Application filed September 30, 1913. Serial No. 792,677.

To all whom it may concern:

Be it known that I, FREEMAN S. HUNTER, a citizen of the United States, residing at Bedford, in the county of Lawrence and State of Indiana, have invented a new and useful Metallic Railroad Cross-Tie, of which the following is a specification.

The present invention relates to improvements in metallic ties and rail fasteners, one object of the present invention, being the provision of a tie, composed of two counterpart members, each of which is provided with interlocking means for maintaining the tie members together and for properly holding the two rails spaced against spreading or inward movement, the present tie being readily positioned in place and the rails secured thereto without the use of spikes or the like.

A further object of the present invention is the provision of a metallic tie, composed of two similar members, the portions of which beyond the rails are of greater width than the intermediate portions, which are disposed to lie in parallel and in slightly different plane, the extreme ends being constructed to engage the inner base flange of the rails and thus hold the rails properly seated and against inward displacement, there being novel means provided for locking the respective members together against transverse and longitudinal displacement when the members are assembled.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a view in elevation showing the present tie and rail fastener in use, the two rails being shown in cross section. Fig. 2 is a top plan view of the tie fastener shown in Fig. 1. Fig. 3 is a top plan view of one of the members of the tie. Fig. 4 is a side elevation of a member of the tie slightly modified to accommodate a switch rail. Fig. 5 is an enlarged detail sectional view taken on line 5—5 of Fig. 2. Fig. 6 is an enlarged detail top plan view of the present tie and rail fastener when

used in connection with a switch. Fig. 7 is an enlarged plan view of a modified form of tie and rail fastener. Fig. 8 is an enlarged sectional view taken on the line 8—8 of Fig. 2.

Referring to the drawings, and particularly to the structure shown in Figs. 1-6, the two members 1 and 2 are constructed similarly, being provided with the enlarged portion 3 adapted to be disposed exteriorly of the rails R, the recessed or notched portion 4 being provided as clearly shown. Each member is provided with the reduced portion 5 which is disposed as a continuation of one side of the portion 3 thereof, and approximately one-half the width of the complete tie, so that when the members are assembled, as clearly shown in Figs. 1 and 2, the members 5 will be disposed in parallel in plan, and will be crossed as illustrated in Fig. 1. Each member 1 and 2 has a projecting portion at the base of the reduced portion 5, which portion 6 is provided with the truncated pyramidal aperture 7, as clearly shown in Figs. 3 and 8. That portion 8 which serves as a rail seat is provided with a depression 9 to receive a suitable rail cushion, the rail being clamped in place by means of the rail base engaging plate 10 which is bolted or otherwise secured to the portion 3 of each member. As shown at the right in Figs. 1, 2 and 4, integral lugs 10' may be employed in lieu of the detachable plate 10. In the depression 9 is adapted to be inserted a block of wood or other resilient material, which cushions to a great extent the base of the rail. The extreme end of the member 5, as at 11 is rabbeted to fit upon the recessed portion 6 of the opposite member and to engage the inner flange of the base of the rail, as clearly shown in Figs. 1 and 2, so as to properly hold the rail seated against the respective members 10 or 10'. The free end of each member 5 has a wedge-shaped or dovetailed lug 12 to enter the opening 7, and in order to hold the members interlocked, a steel locking key 14 is inserted between the members 5 and into the aperture 7 the steel locking key as clearly shown in Fig. 5, being provided with the outwardly tensioned spring fingers 13, which engage the tapered walls of the aperture 7, and thus lock the two members 1 and 2 assembled. In order to detach the locking key 14 from

the aperture 7, a clamping device as shown at C in Fig. 5, is disposed to embrace the same and clamp the resilient fingers 13 toward the body of the key 14 whereupon the 5 key may be withdrawn from the aperture 7. The lower ends of the locking fingers 13 are rounded, so that the same will be properly guided into the aperture 7 to normally expand after the same is seated in 10 the position, as clearly shown in Figs. 1, 2 and 5. By means of the notches 4, a crow-bar may be used to adjust the tie relatively to the road bed and ballast.

In Fig. 6 is shown the relative position 15 of a switch rail R' when used in connection with the present tie, the portions 5 being cut away as seen in Fig. 4 to permit the switch rail to set thereon.

In order to provide a safety means to hold 20 the twin members of the tie against outward displacement, the interlocking hooks 15-15' are formed from the reduced portions 5 of each member 1 and 2, and interlock as clearly shown in Figs. 1 and 2. These hooks 25 however, may be dispensed with but they provide an extra means for holding the members properly assembled and as before stated against outward displacement. It also renders easy assemblage of the component parts of the tie before the insertion of 30 the locking key 12 in place.

In the form of tie shown in Fig. 7, the members 1^a and 2^a are constructed similarly, each being provided with two spaced reduced terminals 5^b and 5^c, respectively, which interlock, as clearly shown, the inner free ends thereof coacting as in the other structures and forming with the rail fastening plate 10^a, a means for holding the rail 40 properly seated upon the tie. By this means, the relative width of the tie is greatly increased, as the tie is practically double the width of that shown in Fig. 2.

What is claimed is:

45 1. A rail tie and fastener, composed of two members, each of which has a relatively wide rail base receiving portion and a long terminal, the terminals of both members being disposed in parallel relation to each 50 other with their free ends resting upon the inner base flange of the two rails, an outer base flange receiving means carried by the rail base receiving portion of each member, each rail base receiving portion adjacent the 55 point of overlap with the free end of the long terminal of the other member being provided with an aperture, a locking lug

carried by the free terminal of each member for introduction within the aperture, and a wedging means for wedging the locking lug 60 in its respective aperture to hold the free end of each long terminal downwardly and upon the coöperating base receiving portion of the opposite member.

2. A rail tie and fastener, composed of 65 two members, each of which has a relatively wide rail base receiving portion and a long terminal, the terminals of both members being disposed in parallel relation to each other with their free ends resting upon the 70 inner base flange of the two rails, an outer base flange receiving means carried by the rail base receiving portion of each member, coöperative means carried by the free end of each long terminal and the adjacent portion 75 of the rail base receiving portion of the other member to hold the members in rail base engagement, and a hook carried by the inner face of each long terminal whereby when the members are in rail base engagement the two hooks interlock to hold the members against longitudinal displacement.

3. A rail tie and fastener, composed of 80 two members, each of which has a relatively wide rail base receiving portion and a long 85 terminal, the terminals of both members being disposed in parallel relation to each other with their free ends resting upon the inner base flange of the two rails, an outer base flange receiving means carried by the 90 rail base receiving portion of each member, each rail base receiving portion adjacent the point of overlap with the free end of the long terminal of the other member being provided with an aperture, a locking lug 95 carried by the free terminal of each member for introduction within the aperture, a wedging means for wedging the locking lug in its respective aperture to hold the free end of each long terminal 100 downwardly and upon the coöperating base receiving portion of the opposite member, and a hook carried by the inner face of each long terminal whereby when the members are in rail base engagement the 105 two hooks interlock to hold the members against longitudinal displacement.

In testimony that I claim the foregoing as my own, I have hereto affixed my signature in the presence of two witnesses.

FREEMAN S. HUNTER.
